UNITED STATES PATENT OFFICE.

LEO STEIN, OF NEW YORK, N. Y., AND WILLIAM A. SPARKS, OF HOBOKEN, NEW JERSEY, ASSIGNORS TO THE NATIONAL CASKET COMPANY, OF HOBOKEN, NEW JERSEY.

DESIGN FOR A BURIAL-CASKET BODY.

SPECIFICATION forming part of Design No. 28,149, dated January 11, 1898.

Application filed November 17, 1897. Serial No. 658,871. Term of patent 7 years.

To all whom it may concern:

Be it known that we, LEO STEIN, of New York, county and State of New York, and WILLIAM A. SPARKS, of Hoboken, in the 5 county of Hudson and State of New Jersey, citizens of the United States, have invented and produced a new and original Design for a Burial-Casket Body, of which the following is a specification, reference being had to the 10 accompanying drawing, forming part thereof.

The drawing is a perspective view of a burial-casket body, showing our new design.

The leading or material feature of our design consists of a casket-body A, having columns B at its corners, as shown in the drawing. The bases of the columns B are curvilinear in form and intersect the base-moldings a of the casket-body, and the upper extremities b of the columns intersect and merge

with the top moldings a' of said body. The 20 columns B are also arranged so as to project beyond the sides a^2 of the body A, as shown.

Having thus fully described our invention, what we claim as new, and desire to secure by Letters Patent, is—

25

The design for a burial-casket body substantially as herein shown and described.

In testimony whereof we have hereunto signed our names, in the presence of two attesting witnesses, at the city of Hoboken, in 30 the county of Hudson, in the State of New Jersey, this 16th day of October, 1897.

LEO STEIN.
WILLIAM A. SPARKS.
